PASTRY CUTTER

Ernest J. Camos, 9078 Villaridge Court,
St. Louis, Mo. 63123

Filed June 1, 1970, Ser. No. 23,249

Term of patent 7 years

Int. Cl. D7—99

U.S. Cl. D44—1

FIG.1

FIG.4

FIG.2 FIG.3

FIG.5

FIG.6

FIG. 1 is a side elevation view of the pastry cutter showing my new design;

FIG. 2 is a sectional view taken along line 2—2 of FIG. 1;

FIG. 3 is an end elevational view;

FIG. 4 is a top plan view;

FIG. 5 is a perspective view; and

FIG. 6 is a sectional view taken along line 6—6 of FIG. 1.

I claim:

The ornamental design for a pastry cutter, substantially as shown.
